UNITED STATES PATENT OFFICE

JULIUS KINDERVATER, OF NEW YORK, N. Y.

BOILER

Application filed November 24, 1925. Serial No. 71,171.

This invention relates to boilers, and particularly to boilers designed for use on locomotives. More particularly the invention relates to improvements in combined water-tube and fire-tube locomotive boilers of that basic type shown in my prior Patent No. 910,133, dated January 19, 1909, wherein the fire-box is formed, and the heating surface of the boiler is increased and higher efficiency obtained, by the use of upper and lower drums extending between front and rear water chambers or legs, and water-tubes associated with said drums and water legs, said tubes being so arranged that sets or rows of the tubes themselves form certain walls of the fire-box, and said parts as a whole being so operatively combined as to constitute in conjunction with a grate or its equivalent the boiler fire-box per se with which the fire-tubes communicate in the usual manner, whereby a maximum water heating and steam generating surface is presented to the heat of the fuel and products of combustion, a freer water circulation and the more rapid generation of steam at higher pressure obtained, and a much greater proportion of the heat utilized than was possible with prior locomotive boiler constructions. The present structure, like that of my aforesaid prior patented structure, is also designed to provide a high-efficiency boiler of the described type which is adapted for use in connection with superheaters of accepted design and standard type in general use.

One object of my present invention is to provide a construction which still further increases the heating surface and the efficiency of the boiler.

Another object of my invention is to provide a boiler of greater simplicity than those in use, which is cheaper of construction, and in which the cost of maintenance is reduced.

Still another object of the invention is to provide a boiler giving a still better flow for maximum freedom of circulation of water and steam and the feed of the steam to the superheater elements and cylinders, and in which more ready access is afforded to all parts for convenience in inspection, cleaning, making repairs, etc.

Still another object of the invention is to provide a boiler in which the use of stay-bolts may be largely if not entirely eliminated.

Still another object of the invention is to improve generally upon and to further increase the efficiency of boilers of this type.

With these and other objects in view, the invention consists in the novel features of construction, combination and arrangement of parts, hereinafter fully described and claimed, and as shown in the accompanying drawings, in which:—

Figure 1 is a central longitudinal section through my improved boiler and fire-box, the grate being omitted for clearness.

Figure 2 is a transverse section taken substantially on the line 2—2 of Figure 1.

Figure 3 is a transverse section taken substantially on the line 3—3 of Figure 1.

Figure 4 is a detail horizontal section taken substantially on the line 4—4 of Figure 1.

Referring now more particularly to the drawings, 1 designates the forward barrel or feed-water-heater portion and 2 the rear steam-generator or fire-box portion, of the boiler, said boiler portions being joined at their point of connection by the front water leg 3 and the steam-generator or fire-box portion 2 having at its rear end the rear water leg 4. As specifically shown, the front water leg 3 comprises a front sheet 5 and a back flue sheet 6, said sheets being united at their outer edges to a continuous annular foundation ring 7, while the rear water leg 4 comprises a door sheet 8 and a back sheet 9, united at their outer edges to a continuous annular foundation ring 10. By the use of these continuous annular foundation rings 7 and 10, to which the sheets are riveted, welded or otherwise suitably secured, the sheets of each water leg are held properly and firmly spaced at all points about their margins and greater strength and simplicity of construction secured. The sheet 5 is flanged outward at 5^a to receive and overlap the rear edge of the barrel portion 1, which is riveted or otherwise secured thereto, while the sheet 6 is formed in line with the firebox with an opening 11, the marginal wall of which is cut-

70

75

80

85

90

95

100

turned to form a flange 12 which overlaps and is riveted or otherwise suitably secured to the rearwardly extending flange 13 of a flue sheet 14 apertured to receive and support the rear ends of the fire-tubes 15, disposed within the barrel portion 1 in the usual manner. The flue sheet is thus offset slightly in a forward direction from, but is arranged to lie close to and substantially in the plane of, the rear sheet 6 of the front water leg, and wholly in the plane of said water leg. By this construction and mode of mounting and arranging the flue sheet 14, and by forming the combustion chamber within the fire-box portion 2, as hereinafter described, the use of a combustion chamber extending forwardly into the barrel portion 1 is avoided, thus enabling longer fire-tubes and superheater tubes to be used with the result of securing greater heating surface. The flue sheet section 14 is, furthermore, made of novel form, being curved on the arc of a semi-circle at its base and sides and on an elliptical arc at its top, giving a great expanse of surface both vertically and transversely for the formation of flue holes, so that a larger number of fire-tubes may be used and the heating surface further increased. This general construction of all the parts above-described is of further advantage in simplifying the construction to a material degree and obviating complex and expensive flanging of plates, ensures a staunch and durable connection of the parts, and eliminates the use of the numerous stay-bolts commonly employed. Flanged portions of the sheets 8 and 9 are suitably formed and lapped to provide a fuel opening 4^a.

While the sheets 6 and 14 are described as separate sheets, combined as set forth, it is to be understood that, within the broad aspect of the invention, these sheets may be regarded as one, except when otherwise specifically designated in the claims, the part 6 being in effect the body of the sheet and the part 14 an offset portion thereof, which, for greater convenience of manufacture, are separately formed and united to produce the structure shown and described. Also, while I have described the boiler portion 2 as a "steam-generator" or "fire-box" portion, it is to be understood that under such term or terms is to be contemplated any heat generator or heating chamber forming as a whole a continuous "fire-box" or which encloses or includes both a "fire-box" and a so-called "combustion-chamber". It is further to be understood that, within the broad aspect of the invention and except when specifically designated in the claims, the barrel 1 and water leg 3, separately or conjointly, provide a water chamber, which may be so termed, at the front of the steam generator, while the water leg 4 or its equivalent in structure and function, provides a water

chamber, which may be so termed, at the rear of the steam-generator.

Extending between the front and rear water legs are a pair of upper drums 16 and a pair of lower drums 17. By reference to Figure 2, it will be seen that the upper drums are larger than the lower, and are disposed relatively close together, while the lower drums are located at the extreme sides of the boiler. This arrangement of the lower drums, while not absolutely essential, is preferable, as it permits of great width of fire-box between the lower drums, and at the same time produces a structure which conforms to the standard shape of the locomotive type of boiler. The method of connecting these drums with the water legs may vary, but the structure shown is preferred as one embodying simplicity with great strength and rigidity of connection. As shown, sheet 6 of the front water leg 3 and sheets 8 and 9 of the rear water leg 4 are cut out to form openings to respectively receive the front and rear ends of each drum 16, and the walls of said openings are turned out to form annular flanges 18 which encircle the drum and are properly fastened thereto. Brackets 19 may also be provided and fastened to the drums and to the barrel and also, if desired, to the outer plates or casing of the fire-box to assist in supporting the drums and to more rigidly fasten these parts together. The forward ends of the drums 16 are fully open and extend through the leg 3 and beyond the same and well into the circumferential course of the barrel portion 1, in order that such rigidity of connection may be made, as well as to carry the steam forward to a desirable point and with great rapidity and facility. The rear end of each drum 16, which passes entirely through the rear water leg 4, terminates substantially flush with the outer edge of the flange 18 of the sheet 9, and in that portion of the drum lying between the sheets 8 and 9, and within the water leg 4, are formed openings 20, extending entirely around the drum and serving to establish communication between said drum and said water leg. Each drum 16 is closed at its rear end by a removable head or cover plate 21 of suitable construction, and bolted or otherwise suitably fastened in position, on removal of which a convenient manhole will be formed, through which ready access may be had for inspection, cleaning and repairs. Both sheets 5 and 6 of the front water leg 3 and both sheets 8 and 9 of the rear water leg 4 are cut out to form openings to respectively receive the front and rear ends of each lower drum 17, and the walls of these openings are outturned to form flanges 22. The ends of each drum 17 are encompassed by these flanges and are suitably fastened thereto, and the front and rear ends of said drum respectively extend through the water legs 3 and 4 and termi-

nate flush with the outer edges of the flanges 22 of the sheets 5 and 9. The portions of these drum ends which are enclosed in the water legs are formed with openings 23, similar to the openings 20 in the drum 16, whereby communication between the drums 17 and the water legs 3 and 4 is established. The opposite ends of the drums 17 are formed or provided with heads 24 having openings 10 therein closed by removable cover plates 25, on removal of which access may be obtained to the drum for inspection, cleaning or repairs. As shown, the sheet 5 may have a barrel receiving opening formed therein corresponding in diameter to that of the barrel 1, from the wall of which opening the flange 5^a extends, and the base of which opening lies above the horizontal plane of the drums 17 and the grate 26. With this construction 15 the drums 16 and all water tubes opening into the barrel through the sheet 6 will communicate directly with the barrel for the more direct, rapid and freer flow of water and steam than would be the case if there were 20 inhibiting obstructions, while at the same time the lower drums 17 are made to communicate with a depressed portion of the water leg 3 lying below the plane of the base of the barrel and the horizontal line of the 25 grate, said depressed drum portion thus forming a transverse well extending between the forward ends of the drums 17 whereby such ends of the drums are connected by a somewhat restricted channel with the barrel and receive the cooler water therefrom. By such 30 provision and arrangement of this restricted channel a more regular and even flow of the water at proper temperature from the barrel to the drums 17 and water tubes connected therewith will be obtained and undesirable 35 surging or jetting in the water heating and steam generating channels under water-head and steam pressures in the barrel prevented. It will be observed that the grate 26, which 40 may be supported in position in any preferred manner, and the drums 17 respectively form the base and the lower portions of the side walls of the fire-box, which is closed at its top by the drums 16 and an intervening layer 45 of fire brick or other heat-resisting material 27 closing the space between said drums above their horizontal centers. Below this layer 27 is arranged a group of horizontal water-tubes 28 beaded into the sheets 6 and 8 and 50 extending between the water legs 3 and 4, these tubes being located in the space between said drums below their horizontal centers and coacting therewith to form the upper or crown wall of the fire-box or fire-box and 55 combustion chamber. The tubes 28 act further as a support for the insulating layer 27, which prevents upward passage of the heat between the drums and tubes and deflects and 60 concentrates the deflected heat against said tubes and the adjacent sides of the drums. 65

Extending between each upper drum and its corresponding lower drum are water-tubes 29 and 30, beaded into the drums. These tubes are disposed in rows (two rows being shown) and may or may not have their ends swaged or reduced, as found desirable. Although they are so shown in the drawings, it is to be understood that I do not wish to be limited to this construction. It is however, desirable that the tubes 30 of the outer 70 row should lie as close together as possible. To this end, therefore, I taper or swage the ends of these tubes to any suitable amount which will adapt the tube ends to be fitted in proper holes in the drums while allowing the adjacent sides of the tubes of the row to closely abut in such manner as to form a solid wall of tubes 30 at each side of the fire-box. As shown, the holes 31 in the drums which receive the ends of the tubes 29 may be spaced to set said tubes a desired distance apart, while the holes 32 in the drums which receive the ends of the tubes 30 are set much closer together. The two outer rows of contacting tubes 30 arranged 75 as described, therefore, form the side walls of the fire-box chamber and the tubes 29 rows of tubes which are arranged on the inner sides of these walls and spaced with relation thereto and to each other, this spacing 80 being such that the heated products of combustion may pass between the rows of tubes 29 and 30 and between the tubes of the row 29. The tubes 30 may be covered by outer plates 32^a between which and the tubes may be placed a layer of suitable insulating material 32^b, and such plates and insulating material may be carried entirely around the fire-box structure to provide an outer enclosing jacket or shell. By spacing the upper 85 drums fairly well apart drums of larger diameter may be used, the width of the fire-box at the top is increased, provision made for the placement of the horizontal tubes 28, the inclination of the tubes 29 and 30 reduced, and very little bending of these tubes 90 required. These tubes 29 and 30 may, in fact, if desired, be disposed in vertical planes at opposite sides of the fire-box beyond the line of the outer sides of the upper drums, 95 requiring the inward bending of their upper ends only to connect with the upper drum, so that additional space will be afforded between the opposite rows of tubes 29 for the 100 reception of a header or intermediate auxiliary water leg and a series of auxiliary tubes, as hereinafter described, and in order to secure a better circulation of the flames and products of combustion from the fuel in the grate whereby greater heating efficiency is 105 obtained. Between the water legs 3 and 4 each drum 17 is provided with spaced bottom wall portions 33, but is otherwise normally open, the open portions being closed by 110 detachable caps or cover plates 34 secured in 115

120

125

130

position by bolts 35. The wall portions 33 carry drain plugs 36, for draining off loose sediment and impurities when desired. Upon removal of the cover plates and plugs 5 the lower ends of all the tubes 29 and 30 may be exposed for inspection and for ready convenience in making repairs, etc. Such exposure of the tube ends will also permit 10 of the use of rakes or of turbine or other cleaners being used to scrape the above-mentioned tubes or to permit said tubes or the entire circulating system to be washed out for the removal of scale or other impurities when required.

15 A depending vertically disposed header, water-table baffle or auxiliary water-leg 37 is arranged transversely of the fire-box beneath the drums 16 with its ends terminating above the drums 17. This header or auxiliary water leg 20 is positioned near the front of the fire-box adjacent to but some little distance in rear of the rear sheet 6 of the water leg 3. This header is provided at its top with hollow spaced brackets 38 riveted to the bottoms of 25 the respective drums 16, and each forming a passage or channel communicating with the drum to which it is attached through a plurality of openings 39 in the drum wall. Extending longitudinally through the fire-box 30 are horizontal rows of auxiliary water-tubes 40 connecting at their rear ends with the water leg 4 and at their front ends with the header 37. As shown, the tubes of these rows are spaced for passage of the products of 35 combustion between them but are staggered in arrangement in order that the products of combustion in passing between them must take sinuous or circuitous courses, and as these tubes are located centrally of the fire-box, 40 where the temperature is highest, they will be heated to an intense degree. The tubes are also preferably inclined at a slight upward and rearward angle between the water legs 37 and 4 in order to facilitate the travel of the 45 generated steam while slightly retarding the flow of the water for a most efficient time period of action of the heat thereon, thereby securing rapid generation of steam within a short range of travel of the water. Through 50 this arrangement of the tubes 40 and their mode of connection with the drums 16 and 17 and water legs 4 and 37, and the described association of the drums 16 and 17 and tubes 29 and 30, a compact organization of water circulating and steam generating surfaces is 55 produced which ensures free flow of the water and steam and release of the latter as fast as generated, a sufficient retardation in the flow 60 of the water to ensure its rapid generation into steam without undue water travel or water lag, and the transmission of the heat to a most extensive heating surface the elements of which are so combined and arranged 65 as to utilize to a most efficient degree all of the

available heat for heating the water and generating steam.

A second set of horizontal water-tubes 41, arranged at equidistant intervals across the fire-box, connect at their forward ends with 70 the sheets 6 and communicate with the base or well portion of the front leg 3, and said tubes thence extend rearwardly at an upward angle through the fire-box to the door sheet 8 to which their rear ends are connected, said 75 ends communicating with the rear water leg 4. Supported by these tubes is a similarly inclined baffle plate or fire wall 42 of fire-brick or other suitable refractory material. This 80 baffle plate extends transversely between the rows of tubes 29 and longitudinally from the base of the forward end of the fire-box a distance rearwardly from two-thirds to three-fourths the length of the fire-box, its rear end abutting the lower tubes 40 and terminating 85 in advance of the rear water leg 4 to provide an intervening passage 43 for the upflow of the products of combustion from the grate. The baffle plate protects the sheets 6 and 14 and the header 37 from the concentrated heat 90 of the flames and directs the flow of the flames and products of combustion through a sinuous course in order that a most efficient application of the heat to the heating surfaces may be obtained. This course of flow of the 95 flames and products of combustion is indicated by the arrows in Figure 1, from which it will be seen that the products flow upwardly and rearwardly from the bed of fuel on the grate toward the rear of the fire-box, upward 100 through the passage 43 and between the tubes 40 and against the surfaces of the drums 16 and tubes at the rear of the fire-box, and thence forward toward the front water leg 3, a portion of the products flowing straight forward along the surfaces of the drums 17 and tubes over the top of the header 37 and down 105 into a combustion or flue chamber 44 formed between the flue sheet 14, the header and the forward end of the baffle plate 42, and the remainder of the products flowing forwardly along the tubes 40, against the rear wall of the header 37, which acts as a baffle at this point, and thence downwardly into the chamber 44 110 through the passage 45 formed between the base of the header 37 and baffle plate 42, the flames and products thus entering the chamber 44 striking against the flue sheet 14 and flowing through the fire tubes 15. Thus all of 115 the water heating and steam generating surfaces of the fire-box will be subjected either to the direct heat of the bed of fuel or to the intense heat of the flames and products of combustion therefrom in such a manner that a very large proportion of the available heat 120 will be efficiently utilized for the continuous and rapid generation of steam in large volume and at high pressure, that proportion of heat not utilized for steam generation in the fire-box serving, on its passage through the fire 125 130

tubes 15 and into the smoke-box, to heat the water in the barrel 1 and to superheat the previously generated steam through superheater tubes or units disposed in certain of the tubes 15 in the usual way. Waste of heat from the fuel is, therefore, reduced to the minimum and a high-efficiency locomotive boiler of economical type, in both construction and operation, produced,—and one in which the generation of superheated steam at high working temperature as rapidly as needed for the largest and highest powered locomotives is assured at a comparatively low operating cost. It will be observed that this boiler construction is such that it may be employed without modification for the use therewith of steam superheating elements of known efficiency and standard type, which superheater elements may be employed without variation from those used in common practice, a very important and desirable feature of this invention, as will be readily understood and appreciated by those versed in the art.

The described arrangement of the header-baffle 37 is, furthermore, of advantage for regulation of the draft. The location of the header adjacent to the entrances of the fire-tubes or flues 15 checks the draft at this point, but this is compensated for by the provision of the chamber 44 and the increase in the number of fire-tubes 15 permitted by the construction of flue sheet 14 previously described. Induced by the draft from the stack there is a tendency for the formation of a partial vacuum in the chamber at the entrance to the tubes 15, as a result of which a powerful draft will be created at this point, through which double draft action the combustion of the fuel and circulation of the gases in the fire-box will be promoted and the flow of the gases at ample velocity through the tubes 15 ensured. It will be understood, of course, that by making the flue sheet 14 independent of the inner sheet of the front water leg and securing it thereto as set forth, such flue sheet may be of metal thicker than the body of the inner sheet or of a metal of greater heat resistivity than the metal of the body of the inner sheet. In either case a flue sheet of greater durability than the sheet body may be used so that the flue sheet may be placed at the front of the fire-box without liability of its more or less rapid disintegration under the intense heat of the products of combustion from the fuel. This allows the combustion chamber to be disposed at the front of and within the fire-box instead of forming it as a special chamber projecting forwardly beyond the front water-leg and into the barrel. As a result the barrel is given greater water containing capacity and the heat concentrated to a greater extent in the fire-box and longer fire tubes and superheater tubes may be used. The flue sheet arrangement described also permits of the disposition of the header 37 at

the rear of the combustion chamber 44 so as to form a wall thereof and a shield to protect the sheets 6 and 14 to a large extent from the more intense heat of the flames, as well as the spacing of the header with relation to the sheet 14 to form a chamber 44 of correct size and to secure the beneficial draft action above set forth. Furthermore, as the sheet 14, though arranged at the front of the combustion chamber, is at the same time disposed in the front water-leg, the sheet is protected also by the cooling action of water of a temperature sufficiently low to prevent it from being unduly heated and yet sufficiently high to prevent undue cooling and warping or cracking of the sheet, whereby all the aforesaid advantages are secured while the life period of usefulness of the flue sheet is prolonged.

It is regarded as desirable to omit the use of tubes 29 between the ends of the header 37 and flue sheet 14, and to correspondingly omit the same number of tube receiving openings 31 in the drums 16 and 17. (See Figures 1 and 4.) By this means the base portions of the ends of the header 37 may be extended laterally beyond the lines of the tubes 29 to cover the full distance between the tubes 30 for a more efficient baffling action. This also allows an opening 31' to be placed in each drum in line with the openings 31 to receive the ends of the tubes 37' which will thus lie in line with the tubes 29. The omission of the tubes 29 at the sides of the chamber in advance of the header 37 and between the same and the sheet 14 further allows freer flow of the products of combustion over the surfaces of the tubes 30 lying in advance of the header 37 fully up to the sheet 14, as well as the mingling of the currents of the products of combustion in the chamber and their passage to the tubes 15 without undue back-lash or interference with their flow or interference with the draft. The arrangement of the header thus described allows the lower corners thereof to contact directly with the tubes 30, from which points the ends of said header preferably slope or incline upwardly and inwardly, as at 37^a, thus decreasing the length of the header in an upward direction, so that above the contact corners passages will be formed between the outer ends of the header and brackets 38 and the tubes 30, as well as between the brackets 38, for the flow of the products of combustion over the ends of the header and centrally over the top thereof in order that all surfaces of the drums 16, tubes 28 and 30, and the header 37 may be effectually heated.

A tube 46 extends between and is beaded at its ends in the sheets 6 and 7 and connects the water legs 3 and 4. This tube is of comparatively large diameter, of much larger diameter than the other water tubes, and is preferably placed at the highest point in the center line of the boiler above and on a line

70

75

80

85

90

95

100

105

110

115

120

125

130

between the drums 16. This tube is consequently arranged above the water-level, which is normally in the region of the center line of the drums 16, and serves as a high level 5 steam conductor to facilitate and promote the rapid feed of the generated steam from the generator to the barrel 1, from which all the generated steam is conducted in any suitable manner to the usual superheater header. The tube 46 further acts as a relief conductor to 10 allow free transference of any surge water from one part of the system to another, thus preventing any interference with the normal water flow or forward feed of steam as fast 15 as generated.

From the foregoing description, taken in connection with the accompanying drawings, the construction and mode of operation of my improved high-efficiency locomotive boiler 20 will be readily understood, and it will be seen that the invention provides a combined water-tube and fire-tube boiler which ensures economy of construction, operation and maintenance of the locomotive, enables steam to be 25 generated rapidly and without the heat losses and service objections inherent in locomotive boilers of ordinary type. This boiler also dispenses with complex and expensive flanging of parts and obviates the use of the multiplicity of stays commonly employed and 30 frequent and expensive repair work incidental to the use thereof. Substantial economy in the use of fuel is also obtained.

I have retained in this improved construction of boiler a feature of importance disclosed in my prior Patent 910,133, referred to, in that the structure of the fire-box as a steam generator permits use of the barrel and its fire tubes or flues 15 as a feed water heater, the water in which is heated from said flues, 40 thus providing for the economical heating of feed water in large volume for immediate use in the generation of steam. The provision made for the use of a larger number of the tubes 15 is of great advantage in allowing 45 of the heating of this feed water without reducing the amount of heat available for superheating purposes, as will be readily understood.

Having thus fully described my invention, 50 I claim:-

1. In a boiler, front and rear water legs, a pair of upper drums and a pair of lower drums communicating with said water legs, 55 vertical tubes connecting each upper drum with a lower drum, a header disposed between the water legs and communicating with both upper drums, and horizontal tubes arranged beneath the upper drums and in a plane between said upper drums and the lower drums and connecting the rear water leg with said header.

2. In a boiler, front and rear water legs, a pair of upper drums and a pair of lower 60 drums communicating with said water legs,

vertical tubes connecting each upper drum with a lower drum, horizontal tubes disposed in the space between the upper drums and connecting the water legs, a header disposed between the water legs and communicating with both upper drums, and horizontal tubes arranged beneath the upper drums and in a plane between said upper drums and the lower drums and connecting the rear water leg with said header. 70

3. In a boiler, a front water leg, a rear water leg, a barrel, a fire-box structure between said water legs including a pair of upper drums, a pair of lower drums, said drums communicating with said water legs, 80 and vertical water tubes connecting each upper drum with a lower drum, a header disposed in said fire-box between said water legs and in communication with said upper and lower drums, and horizontally arranged water tubes extending longitudinally of the fire-box between the header and rear water leg and disposed beneath the upper drums. 85

4. In a boiler, a front water leg, a rear water leg, a barrel arranged in advance of the front water leg, a fire-box structure between the water legs and including a pair of upper drums, a pair of lower drums, and water-tubes connecting each upper drum with a lower drum, said drums being in communication 90 at their opposite ends with the water legs and the upper drums extending beyond the front water leg into the barrel, a header in the fire-box structure at a level between the upper and lower drums and communicating 100 with both pairs of drums, a set of horizontal water-tubes extending longitudinally of the fire-box between the upper drums and connecting the front and rear water legs, and a set of horizontal water tubes extending longitudinally of the fire-box and connecting the rear water leg with the header. 105

5. In a boiler, a front water leg, a rear water leg, said water legs comprising front and rear sheets, the rear sheet of the front water leg having an opening, a barrel connected to and extending in advance of the front water leg, a fire-box structure between the water legs including a pair of upper drums and a pair of lower drums connected to the front and rear water legs, and vertical water-tubes connecting each upper drum with a lower drum, a flue sheet closing the opening in the rear sheet of the front water leg and lying in advance thereof in the plane between the sheets of the said water leg and extending the distance between the upper and lower drums, fire-tubes connected with said sheet and extending into the barrel, a vertical transverse header disposed in the fire-box adjacent to and in rear of said sheet and forming a baffle, said header communicating with the drums, a horizontal row of water-tubes connecting the rear water-leg with the header, a second horizontal row of upwardly and 120

75

5 rearwardly inclined water-tubes connecting the front and rear water legs, a grate in the fire-box, and a baffle disposed at the front of the fire-box above the second-named row of horizontal water tubes and between the same and the header and first-named horizontal row of water tubes.

6. In a boiler, a pair of upper drums, a pair of lower drums, a row of vertical water tubes connecting each upper drum with a lower drum, said drums and tubes constituting component parts of a fire-box, heating means in the fire-box, a transverse header in the fire-box and connecting a pair of the drums, tubes connecting said header with the drums of the other pair, a rear water chamber in communication with the rear ends of the drums, a front water chamber with which the forward ends of the drums communicate, a flue sheet disposed at the rear of the front water chamber, and fire-tubes connected with said sheet and extending into said front water chamber, said flues receiving the products of combustion passing from the fire-box.

7. In a boiler, a pair of upper drums, a pair of lower drums, a row of vertical water tubes connecting each upper drum with a lower drum, said drums and tubes constituting component parts of a fire-box, a barrel in advance of the fire-box, heating means in the fire-box, a rear water chamber in communication with the rear ends of the drums, a front water chamber, a third water chamber separate from the walls of the fire-box and arranged in said fire-box between the upper and lower drums, said third water chamber extending edgewise in a vertical plane and lengthwise transversely of the fire-box and communicating with the rear water chamber and directly with the upper drums, tubes connecting said third water chamber with the lower drums, a flue sheet at the rear of said front water chamber and extending vertically between the drums, the upper drums having their forward ends extending through said sheet into the front water chamber and the lower drums having their forward ends extending forwardly through said sheet and communicating with the front water chamber, and fire-tubes connected with said sheet and through said front water chamber and into the barrel, said flues receiving the products of combustion passing from the fire-box.

8. In a boiler, a pair of upper drums, a pair of lower drums, a row of vertical water tubes connecting each upper drum with a lower drum, said drums and tubes constituting component parts of a fire-box, heating means in the fire-box, a rear water chamber in communication with the rear ends of the drums, a front water chamber, a barrel communicating at its rear end with the front water chamber, a transverse header in the

fire-box between the upper and lower drums and connecting a pair of the drums, tubes connecting said header with the drums of the other pair, a flue sheet at the rear of said front water chamber and extending vertically between the upper and lower drums, the upper drums having their forward ends communicating through said sheet with the front water chamber and the barrel and the lower drums having their forward ends extending through said sheet and communicating with the front water chamber, and fire-tubes connected with said sheet and extending through said front water chamber and into the barrel, said flues receiving the products of combustion passing from the fire-box.

9. In a boiler, a pair of upper drums, a pair of lower drums, a row of tubes connecting each upper drum with a lower drum, a rear water leg communicating with both the upper and the lower drums at their rear ends, a front water leg in communication with the forward ends of both the upper drums and the lower drums, said drums, tubes and water legs forming constituent parts of a fire-box, a barrel arranged in advance of the fire-box and connected to the front water leg, a supplemental water leg in the fire-box and communicating with the upper and lower drums.

10. In a boiler, front and rear water legs, each including inner and outer sheets, upper and lower drums communicating at their ends with the water legs, water tubes connecting each upper drum with a lower drum, heating means between the lower drums, a barrel connected with the outer sheet of the front water leg, the rear sheet of said front water leg having a flue sheet portion offset therefrom and lying in the plane of said water leg and between the front and rear sheets thereof, a third water leg arranged between the heating means and upper drums and forming a baffle spaced from said heating means and upper drums and lying close to but in rear of said offset flue sheet portion so as to provide a combustion chamber therebetween, water conducting connections between said third water leg and the upper and lower drums, and a bank of fire-tubes connected with said offset portion of the front water leg and extending into the barrel, the vertical range of said bank of fire-tubes being approximately equal to the full distance between the upper and lower drums.

11. In a boiler, front and rear water legs, each including inner and outer sheets, upper and lower drums communicating at their ends with the water legs, water tubes connecting each upper drum with a lower drum, heating means between the lower drums, a barrel connected with the outer sheet of the front water leg, the rear sheet of said water leg being provided with an offset portion

lying in advance thereof and in the plane of the water leg between its front and rear sheets, a third water leg arranged between the heating means and upper drums and forming a baffle spaced from said heating means and upper drums and lying close to but in rear of said offset flue portion so as to form a combustion chamber therebetween, water conducting connections between said third water leg and upper and lower drums, and fire-tubes connected with said offset portion of the inner sheet of the water leg and extending forwardly through said water leg and into the barrel.

12. In a boiler, a rear water leg, a barrel, a steam generator therebetween including upper and lower drums communicating with the water leg and barrel, and tubes connecting the upper and lower drums, and a high-level steam conductor extending longitudinally between the water leg and barrel above the normal water and steam levels of said steam generator.

13. In a boiler, front and rear water legs, a steam generator therebetween including a pair of spaced upper drums and a pair of spaced lower drums communicating with the water legs and water tubes connecting each upper drum with a lower drum, a barrel communicating with the front water leg, and a high-level steam conductor extending longitudinally between the water legs above the level of the water and steam spaces of the upper drums.

14. In a boiler, front and rear water legs, a steam generator therebetween including at least a pair of upper drums and at least a pair of lower drums communicating with said water legs and water tubes connecting each upper drum with a lower drum, and a high-level steam conductor connecting said water legs above the highest water and steam levels of said steam generator.

15. In a boiler, a fire box shell including side walls, a steam generator in said shell including upper and lower drums and rows of inner and outer water tubes connecting the upper and lower drums at each side of the generator, said lower drums being arranged on the inner sides of and adjacent to the lower edges of the side walls of the shell and each lower drum comprising a body of substantially circular cross section and having in its top longitudinal rows of openings lying respectively centrally of said body and between the vertical center and outer end thereof and receiving the lower ends of the tubes, the said body being provided with a flattened lower face terminating above the plane of the lower edge of the adjacent side wall of the shell and having a lateral flange extending beyond the outer side of the drum body and bearing against said wall and also having an opening located between its vertical center and the outer side of the drum body, an insulat-

ing lining on the inner side wall of the shell between said shell and the outer side of the drum body, and a plate detachably secured to said flattened face and closing the opening and extending beneath said flange and in contact with the side wall of the shell with its lower surface substantially flush with the lower edge of the latter.

16. In a boiler, a fire box having a combustion chamber, a barrel, a flue sheet at the front of the combustion chamber and between the same and the rear end of the barrel, a pair of upper and a pair of lower drums in said combustion chamber, water tubes lining each side of the combustion chamber and connecting each upper drum with a lower drum, fire tubes connecting with the flue sheet and extending into the barrel, heating means at the base of the combustion chamber between the lower drums, a baffle subdividing the combustion chamber into lower and upper portions in communication at their rear ends and closed against communication at their forward ends, and a vertical transverse header in said upper portion of the chamber between the baffle and upper drums and spaced therefrom and from the flue sheet and rows of water tubes to provide intervening passages for the flow of the products of combustion, said header being in communication with the upper and lower drums.

17. In a boiler, a fire box shell, a steam generator within the shell including at least a pair of upper and a pair of lower drums and water tubes connecting each upper drum with a lower drum, and a unitary water chamber independent of and spaced from the shell and extending lengthwise transversely of and in the space bounded by said generator and at a point between the front and rear ends thereof, and conductors connecting said chamber at its opposite ends with said pairs of upper and lower drums.

18. In a boiler, front and rear water legs, a fire box shell between said water legs, a steam generator within said fire box shell including a pair of upper drums and a pair of lower drums connected with said water legs, water tubes connecting each upper drum with a lower drum, and heating means arranged between the lower drums, the front water leg including a flue sheet lying within the plane of said water leg, a barrel connected to the forward side of the front water leg, fire tubes connected with said flue sheet and extending into the barrel, a baffle closing direct communication between the heating means and the fire tubes at the front of the fire box and dividing the fire box chamber into upper and lower portions communicating at the rear thereof, a vertical transverse header arranged between said baffle and the upper drums close to and in rear of the flue sheet and spaced from said baffle and drums and the walls of the fire box to form an intervening combus-

- tion chamber and spaced from the drums, baffle and water tubes to provide passages above, below and beyond the ends of the header for the flow of the products of combustion from said upper portion of the fire box chamber to said combustion chamber, and water flow connections between said header and the upper drums and the lower drums.
19. In a boiler, front and rear water legs, a fire box shell between said water legs, a steam generator within said fire box shell including a pair of upper drums and a pair of lower drums connected with said water legs, water tubes connecting each upper drum with a lower drum, and heating means arranged between the lower drums, the front water leg including a flue sheet lying within in the plane of said water leg, a barrel connected to the forward side of front water leg, fire tubes connected with said flue sheet and extending into the barrel, a baffle closing direct communication between the heating means and the fire tubes at the front of the fire box and dividing the fire box chamber into upper and lower portions communicating at the rear thereof, a vertical transverse header arranged between said baffle and the upper drums close to and in rear of the flue sheet to form an intervening combustion chamber and spaced from the drums, baffle, the walls of the fire box and the water tubes to provide passages above, below and beyond the ends of the header for the flow of the products of combustion from said upper portion of the fire box chamber to said combustion chamber, water tubes extending longitudinally in said upper portion of the fire box chamber at an upward and rearward angle of inclination between the header and the rear water leg, and water flow connections between said header and the upper drums and the lower drums.
20. In a boiler, a fire box structure including front and rear water legs, a fire box shell between the water legs and steam generating means within the shell and between the water legs and comprising a pair of upper drums, a pair of lower drums, water tubes connecting each upper drum with a lower drum, and heating means between the lower drums, the front water leg having a flue sheet located in a vertical plane between the front and rear sides thereof, a barrel connected to the front side of and extending in advance of said front water leg, fire tubes connected with the flue sheet and extending into the barrel, a header forming a third water leg disposed adjacent to but in rear of said flue sheet and between the heating means and upper drums, said header being in communication with the upper and lower drums and spaced from the drums, water tubes, walls of the fire box and heating means to provide passages for the flow of the products of combustion about it, and water tubes connecting said header with the rear water leg.
21. In a boiler, a rear water leg, a barrel, a steam generator therebetween including a plurality of upper drums, a plurality of lower drums, and water tubes connecting each upper drum with a lower drum, the upper drums extending forwardly beyond the steam generator and into the barrel, a steam space being formed between said drums and the top of the barrel shell, and a high level steam pipe communicating with said rear water leg and extending therefrom forwardly along the steam generator above the level of the upper drums and discharging into said steam space in the barrel.
22. In a boiler, front and rear water legs, a barrel, a steam generator arranged between said water legs and including a plurality of upper drums, a plurality of lower drums, water tubes connecting each upper drum with a lower drum, and a depending water-table baffle disposed between said front and rear water legs and communicating with said upper and lower drums, the upper drums extending forwardly beyond the steam generator and into the barrel, a steam space being formed between said drums and the top of the barrel shell, and a high level steam pipe communicating with said rear water leg and extending therefrom forwardly along the steam generator above the level of the upper drums and discharging into said steam space in the barrel.
23. In a boiler, a front water leg, a rear water leg, a barrel arranged in advance of the front water leg and connected therewith, a fire box structure between the water legs and barrel, said structure including a pair of upper drums in communication with the water legs and barrel, a pair of lower drums, and side rows of vertical water-tubes connecting each upper drum with a lower drum, a flue sheet at the forward end of the fire box and between the fire box and barrel, fire-tubes connected with said sheet and extending into the barrel, a header in communication with the drums and disposed in the forward portion of the fire box adjacent to said sheet, a grate in the fire box, a baffle in the fire box between the grate and the header, said header being spaced from the flue sheet, the baffle, the upper drums and side rows of water-tubes to provide intervening passages for the products of combustion flowing from the grate to the fire tubes, and horizontal water-tubes connecting the header with the rear water leg.
24. In a boiler, a pair of upper drums, a pair of lower drums, a row of vertical water tubes connecting each upper drum with a lower drum, said drums and tubes respectively constituting component parts of the top wall and the side walls of a fire box, heating means in the fire box, a barrel, a rear water

chamber in communication with the rear ends of the drums, a front water chamber with which the forward ends of the drums and the rear end of the barrel communicate, said chamber including a rear sheet having an opening therein in line with said fire box, a flue sheet closing said opening, a horizontal transverse water chamber arranged in the fire box at a point between the front and rear water chambers and at a level between the levels of the upper and lower drums and communicating with said drums, and fire tubes connected with said flue sheet and extending into the barrel, said flues receiving the products of combustion passing from the fire box.

In testimony whereof I affix my signature.

JULIUS KINDERVATER.
